MACHINE GUN FIRE RETARDER

Oswald O. Sunderland, Fairfield, Conn.

Application September 14, 1945, Serial No. 616,333

14 Claims. (Cl. 89—27)

1
 The invention relates to means for reducing the rate of fire in machine guns, particularly those of .30 and .50 caliber firearms, the object, as usual in such devices, being to enable the use of the standard high rate of fire at which the guns tend to operate with the basic or conventional action, and to permit reduction in this rate at will where the high rate would expend ammunition in a quantity out of proportion to the result accomplished. As is well known, due to the fact that such arms are advantageously usable at short ranges against aircraft, and in order to deliver projectiles at short angular intervals under rapid traverse, the gun action will ordinarily operate at a rate of from 500 to 900 rounds per minute more or less. When such a gun is used against enemy infantry, such a rate is much too fast, and is apt to result in exhausting the ammunition supply while the military unit is still under fire. This liability is contributed to by the tendency of some personnel to "freeze" on the trigger.

Therefore, it is now recognized as important to provide means operable at will be the soldier to control the rate to meet conditions of the moment. In meeting the need outlined, it is an important object of this invention to present a mechanical device which will be peculiarly novel for its simplicity, compactness, and adaptability to be substituted for conventional trigger mechanism without changing conventional gun actions otherwise than to provide for the fitting of a small trigger housing to the conventional receiver.

It is a special aim of the invention to present an escapement device which is safe from liability of access of dirt and mud or damage by moving objects as might be encountered in the rough handling of firearms in field service.

A further aim is to present a novel form of delay device including a novel means for effecting the functioning of an escapement device without dissipating materially the energy of recoil and counter recoil devices of the gun action. Additional objects, advantages and features of invention reside in the construction, arrangement and combination of parts involved in the embodiment of the invention and otherwise, as will be either apparent or understood from the following description and accompanying drawings, wherein:

Figure 1 is a fragmentary longitudinal sectional view of a trigger and delay action device in cocked position, the trigger free, with a part of a conventional action slide such as has been heretofore used in machine guns such as illustrated in the patent to Browning, Number

1,293,022, and to Simpson, Number 2,379,461, and other patents;

Figure 2 is a similar view of the trigger mechanism in retarded automatic fire, at the moment of let-off of the sear;

Figure 3 is a fragmentary view of the trigger parts at initial automatic retarded action position of the rack and sear subject to movement by the slide to the let-off position;

10 Figure 4 is a cross section on the line 4—4 of Figure 1;

Figure 5 is a detail of the escapement wheel and ratchet with a part broken away;

15 Figure 6 is a cross section on the line 6—6 of Figure 1; looking toward the gun butt;

Figure 7 is a section on the line 7—7 of Figure 1, and

Figure 8 is an exploded perspective view of the trigger mechanism.

20 Referring more in detail to the drawings, there is illustrated a portion of a receiver 10 in which is mounted the conventional action slide 11, having the usual recoil and counterrecoil functions, including in the specific instance a buffer 12 against the buffer head 13 of which the cross member or bumper 14 of the slide 11 engages at the rear limit of its recoil. As is usual, in these slides, the cross member 14 includes a bottom planiform plate 15 extending forwardly and having in its lower face the usual notch 16 against the claw or shoulder 17 of which, the heel 18 of a broad sear 19 engages substantially in the same manner that the conventional sear engages in the notch in such a gun action.

35 In the present instance, the trigger frame or housing 20 includes side plates 21 fitting into the receiver conventionally and a forward vertical cross plate 20' of the frame has near its upper edge a horizontal rib 21' serving as a support

40 means, although other construction may be employed as found expedient. A bottom 22 is formed on the housing and below this at the forward part a trigger guard 23 of conventional form is positioned, abutting a hollow pistol grip 24, extending downward from the rear end of the trigger housing.

The sear in the present instance corresponds somewhat to the form of the conventional sear in prior weapons of this type, including a forwardly extending operating leg 26, this and the heel portion 18 of the sear being substantially a straight member thickened toward the heel so as to receive its pivot pin 27 therethrough and to permit the formation of a recess on its underside accommodating a compression coil spring 28 seated on a

seat 38 on a lever 29. Contrary to ordinary practice, however, the pivot of the sear 19 is not fixed in the trigger frame, but is a floating pivot pin 27, set through the upper short arm 25 of the lever 29, the lower long arm of which extends downwardly through an opening in the bottom 22 into the hollow grip 24. On the upper part of this lower arm a rearward cup seat bracket 39 is formed offset slightly to the left but under the heel of the sear (Fig. 7), and receiving therein the lower end of the sear spring 28. This lever 29 is pivoted on a cross pin 31 set in the walls 21 of the trigger frame, the lever being located adjacent the right hand side of the trigger frame. Pivoted also on this pin adjacent the left side of the trigger frame and close beside the lever 29 there is a delay lever 32 extending downwardly below the extremity of the lever 29 and carrying at its lower end a rack sector 33 concentric with the pivot of the lever and meshed with a gear 34 loosely revolvable therebelow on a cross pin 35 set between side plates 36 constituting a part of the trigger frame within the grip 24. This rack and gear are located adjacent the left side of the grip as shown. Revolvable freely on the pin 35, there is also an escapement wheel 37 close beside the right side of the gear. The gear and escapement wheel are formed with abutting complementary ratchet or clutch faces 38, and the gear 34 is capable of sliding movement on the pin 35 toward the left so as to permit it to disengage from wheel 37 on rotation in one direction, the clutch faces having saw teeth 39 operative for this purpose. The gear is held yieldingly in engaged relation to the escapement wheel by means of a compression spring 39 (Fig. 4) accommodated in a concentric recess formed in the left side of the gear and confined by a shoulder 40 formed on the pin 35. It may thus be seen that upon oscillation of the lever 32 to the left from its extreme right hand position shown in Figure 1, the gear may move as an idler without rotating the escapement wheel (see Fig. 5), but upon opposite movement of the lever the clutch teeth 38 will co-engage and rotation of the gear will drive the escapement wheel. It will be noted that the wheel 37 is of much larger diameter than the gear 34, and the rack 33 operates close beside the wheel 37. The lower end of the lever 29 is offset toward the left as at 45 in Figure 7, and its extremity 41 (Figures 1, 2 and 4) moves closely over the forwardly extended part of the rack 33, which is formed at its forward end with an upwardly extended lug 42, to limit forward movement of the lever 29 relatively to lever 32, and also a shoulder 43 at the base of the lever 32 to limit relative rearward movement of the lever 29.

The two levers have seat lugs 45 projected across the medial plane of the frame and recessed to receive therebetween a compression spring 46 by which they are urged apart a distance limited by the lug 42, and yieldable momentarily to forward impact thrust of the action slide against the sear 19, as will be subsequently explained.

The upper arm 25 of the lever 29 is extended forwardly at an angle of about 60 degrees to the horizontal, and is engaged in a longitudinal slot formed through the sear, where it receives therethrough the pin 27, as may be seen in Figure 4. As a result, upon counterrecoil of the slide initial engagement of the sear with the shoulder 47 will occur at the positions of these parts shown in Figure 3, and impact of the slide against the sear will move the sear abruptly forwardly,

slightly compressing the spring 46 momentarily with consequent slight downward movement of the sear pivot as may be understood. However, due to the angular position of the sear pivot 27 with relation to the arm 29, movement of the lever 29 is checked by the spring 46 or the lever 29 engages the shoulder 43, before the sear has cleared the slide and the gun will not fire until the trigger is operated. Due to retardance of the lever 32 (to be explained), the spring 46 will recover with partial return of the lever 29 and sear, but continued pressure of the slide will move the levers 29 and 32 substantially as a unit, to the positions of Figure 1.

Rotation of the wheel 37 is retarded by means of a pendulum weight or escapement lever 47 rockingly mounted on a cross pin 48 in the extreme lower part of the space in the grip 24 and having pallets 49 shaped and set within the path of the teeth of the wheel 37 sufficiently to function as an escapement.

A trigger 50 is shown, constituting a depending finger piece 51 and shank 52, the latter rectangular in horizontal section and transversely bored to receive therethrough the trigger pin 53, which is set across the trigger frame. The trigger includes a forward arm 54 cupped on its underside and confining a trigger spring 55 against the bottom 22 of the trigger frame, and a rear arm 56 offset toward the right to lie beneath the right side of the operating leg 26 of the sear 19, but spaced below and from the sear as shown in Figure 1, by a sear cam 57 which is pivoted on a pin 58 set in the walls 21 of the trigger frame rearwardly of the end of the arm 56. This cam is a simple straight arm extended horizontally forward at initial position of the parts, resting upon the arm 56 of the trigger, and supporting slidably the extremity of the arm 26 of the sear upon the cam's flat upper surface. The thickness of the cam is such that—with the trigger in any position—the arm 26 is always supported by the cam.

The cam 57 is laterally thickened at its rear part so as to extend to the left of the arm 56, and is formed on its underside with two horizontal downwardly facing steps 59 and 60 respectively, the former being higher than, and forwardly of the latter as best shown at Figure 8. Below the cam and aligned therewith, rearwardly of the shank of the trigger, an L-shaped dog 61 is pivoted, on a transverse pin 62 below the arm 56, which also serves as a stop for the dog. The dog has a forwardly extending lower short arm 63 cupped and confining thereunder a spring 64 against the bottom of the trigger frame, and an upstanding arm constituting a rest 65 of a length sufficient to extend above the first step 59 a distance corresponding to the movement of the sear arm 26 to first released position as will be subsequently explained. The spring 64 serves to move the rest 65 under the steps 59 and 60 successively as the cam 57 is pivoted clockwise as viewed in Figs. 1, 2 and 3, to successive positions, so as to support the cam in such positions without disturbance of the sear by wavering movements of the trigger within certain limits. The trigger rear arm is extended full width for a short distance from the shank 52, so as to provide a presser lug 66 over the arm 63 of the dog, so that after operation of the trigger to elevate the cam and permit movements of the rest 65 as stated, on release of the finger pull on the trigger, the lug 66 will press upon

the short arm 63 and return the rest 65 toward initial position.

The extent of firing movement of the trigger 51 is limited by means of a selector 67, which is a simple elongated rectilinear sliding block inserted through an opening 68 in the front wall 21 of the housing immediately over the bottom 22 of the housing, this block being substantially thicker and longer throughout its forward part than at its rear part, this forward part remaining in and closing the opening 68 throughout all operating positions of the selector. The rear part 69 of the selector comprises a flat horizontal, longitudinal extension of reduced height at the lower side of the body of the selector, resting upon the bottom 22 and having an upturned nib 70 at its rear extremity. The selector is held in place by means of a small pin 71 set in the walls of the frame closely over the rear extension 69 limiting forward movement of the latter by engagement of the nib 70 with the pin and limiting the rearward movement of the selector by engaging the shoulder 72 on the latter defining the inner end of the thick forward part of the selector. The selector has two operative positions (one being shown in Figure 1), and it is retained yieldingly in either of these positions by a spring-pressed detent 73 slidable in a shallow bore in the bottom 22, arranged to alternatively engage respective indentations 74 in the underside of the selector body. The rearmost of these indentations is positioned so as to stop the selector at a forward position with its inner extremity forwardly of the end of the arm 54 of the trigger. This arm is provided with a forwardly extending lip 75 which, at the rear position of the selector will engage upon the nib 70 and check downward movement of the trigger when the arm 56 has lifted the cam to that position where the rest 65 may engage under the first step 59 (as in Fig. 3). And when the nib 70 is pulled forwardly to its second position, the arm 54 of the trigger may move to the bottom 22 resulting in elevation of the cam sufficiently for the rest 65 to engage under the second step 60.

In operation, assuming that the weapon has been cocked by drawing the slide 11 rearwardly to the buffer head 13 and then releasing the slide, the trigger being free, at the instant of such release the levers 29 and 32 would be in the position shown in Figure 3, but the trigger parts as in Figure 1, and the sear slightly to the right of its position in Figure 1. The usual operating spring of such weapons will then, by its stable force, move the slide 11 and sear forwardly, bringing the parts to the positions illustrated completely in Figure 1, the trigger meanwhile remaining without movement and without being affected, in the position shown in Figure 1. It may also be assumed that the selector has been pressed inward to first, or retarded rate position, as in Figure 1.

Upon pulling the trigger then to the first firing position (see Figure 2) the arm 56 bears upwardly upon the cam 57 and this produces a magnified movement of the leg 26 of the sear until let-off occurs at the instant when the rest 65 is moved by the spring 64 to position under the first step 59, and the heel 18 clears the shoulder 17. The slide is thus released, and moves forwardly to battery position, being returned by recoil or gas operation according to the type of gun involved. With the trigger maintained in or near the first firing position, the leverage exerted through the arm 26 by the cam 57 and the force applied

thereby through the spring 28 to the lug 30, causes the lever end 41 to press forwardly against the lug 42 of the rack, rapidly moving the latter and the lever 32 forward as a unit with the lever 29, and bringing the rack 33 to its forward position (Figure 3), thereby rotating the gear 34 counterclockwise as an idler. Upon recoil of the slide thereafter, the lever arm 25 being now at the maximum elevation of retarded fire, the heel 18 will have been lifted to a level where it will engage the shoulder 17 of the counter recoiling slide.

Incident to the acceleration which may occur after the bumper 14 is stopped by the buffer, the impact of the shoulder 17 against the heel of the sear will for the moment exceed the stable expansive pressure of the conventional driving spring of the gun action, then the sear and lever 29 will be moved and the spring 46 will yield to the pressure of the lever 29 before inertia of the lever 32 (initially positioned as in Fig. 3) and escapement are overcome, permitting a slight convergent movement of the lever. But the spring 46 will immediately thereafter recover and force the lever 29 forward to its initial angular relation to the lever 32, its end 41 stopped against the shoulder 42, while the retarded movements of the rack and ratchet proceed.

The stable force of the driving spring acting through the slide will now continue to move the sear forwardly, swinging the arm 25 forward and the lever 29 rearwardly so that the spring 46 moves the lever 32. This will rotate the escapement wheel 37 clockwise, this motion is impeded by the escapement to a degree determined by the weight of the pendulum and depth of engagement of the pallets thereof with the teeth of the wheel. After the desired extent of movement of the wheel 37 and time lapse required, swinging of the arm 25 and sliding of the sear arm 26 upward on the cam 57 lowers the heel 18 of the sear to a level where let-off will again occur (the trigger being maintained in sufficiently finger-pressed or pulled condition) and the foregoing action will then be repeated as long as the trigger is held to or near its first let-off position. The engagement of the rest 65 before the step 59 will prevent lowering of the cam 57 and operating leg 26 until the trigger is fully released, so that if partial return movement of the trigger occurs no premature engagement of the sear with the slide will be caused after initial let-off.

The spring 46 is of sufficient strength to oppose depression by the stable force of the slide when stopped at initial position so that the levers 29 and 32 normally remain fixed in the relation shown in Figure 1. But in automatic fire on counterrecoil of the slide from the buffer, the component of inertia of momentum acquired by slight acceleration of the slide, which must be additionally overcome when the sear engages the shoulder 17, results in a momentary slight movement of the lever 29 relative to the lever 32, attended by slight compression of the spring 46. The latter quickly recovers, while the sear is still engaged with the slide. If the gun is in course of automatic fire, the rack 33 will first be at a forward position and the arm 25 at a high rearward position, requiring a substantial forward movement of the sear before sliding of the toe of the leg 26 forward and upward on the cam 57—and the forward swing of the arm 25—effect the necessary lowering of the heel of the sear to clear the slide. As soon as let-off occurs with the trigger depressed, the leverage of the leg 26

against the cam 57 and force thereby transmitted through the spring 28, to the lever 29 and so to the lever 32, again swings the rack 33 quickly forward, the force of the spring 28 maintaining this leverage throughout all positions of the parts, including released position of the trigger. In consequence, the rack 33 is always maintained in its forward position when the sear is not engaged by the slide, ready for its delay function with the gear and escapement whenever the sear becomes engaged by the slide.

It will be seen that let-off of movement of the sear is a resultant both of the lowering of its pivot with relation to the frame and rising of the arm 26 in sliding up the top face of the cam 51 while the trigger is pressed to the first firing position (represented by engagement of lip 75 with the nib 70). It is contemplated that the component of motion produced by arm 25 operating translatively on the cam will supply approximately half of the necessary resultant, so that an ample margin for trigger movement will be allowed.

The arrangement has the advantage that a large bearing between the sear heel and slide shoulder 17 is obtained on initial impact, but much less and only slight trigger movement from beginning of take up to let-off required.

When the selector is pulled entirely forward (a position not illustrated) the lip 75 may move to the bottom 22. The greater extent of movement of the trigger permitted thereby causes the trigger arm 56 to elevate the cam and the arm 26 of the sear to such extreme that the heel of the sear is held clear of the slide and does not at any time thereafter engage the slide, as long as the trigger is held depressed to this full position or nearly so. While this condition exists the rapid fire mechanism of the gun being unretarded, operates in its conventional way and at its maximum high rate. The second step 60 would at the same time be engaged by the rest 65, which then functions to prevent partial release of the sear until the trigger is released sufficiently to move the rest 65 to its first firing position (as in Figs. 3 and 2). In the extreme position the action will be stabilized at unretarded automatic operation, and when the release movement indicated occurs the action will become stabilized at retarded automatic fire by engagement of the support 65 under the step 59. At any time that the trigger is partially released to such extent that the pawl may drop to position with the first step 59 engaged on the rest 65 the gun will resume retarded automatic action as first described. At any time that the trigger is completely released the sear will engage and stop action of the gun in the manner first described in reference thereto.

It is an advantage of the arrangement and function of the selector that accidental shifting thereof by engagement thereof against external objects can only result in moving it from high rate to retarded rate position and small likelihood exists that it can be accidentally moved from low rate to high rate position.

It will be understood that in the claims "slide" or "reciprocate" will include pivoted members and/or oscillating movements and devices, such as a pivoted hammer.

I have disclosed the invention with particularity in the best form in which I have yet constructed it, but it will be understood that this is purely exemplary, and that modification and changes in construction and arrangement, substitution of

materials and equivalents mechanical or otherwise may be made without departing from the spirit of the invention set forth in the appended claims, wherein I claim:

5 1. In a firing mechanism, a reciprocating firing member, a sear pivoted thereadjacent having a heel movable and spring-urged into the path of the firing member and having a forwardly extended operating arm, a cam having a cam face under said arm, means responsive to operation of the firing member to move the cam and sear divergently and then convergently with the cam oblique to the path of their relative movement for let-off of the sear, means to retard said convergent movement, and trigger means to move said cam whereby let-off of the sear will occur by at least a terminal part of said convergent movement.

10 2. In a firing mechanism, a reciprocating firing member, a sear pivoted thereadjacent having a heel movable and spring-urged into the path of the firing member and having a forwardly extended operating arm, a cam having a cam face under said arm, means responsive to operation of the firing member to move the cam and sear divergently and then convergently with the cam oblique to the path of their relative movement for let-off of the sear, means to retard said convergent movement, and trigger means to move said cam to a position of greater altitude for let-off at least.

15 3. A retarded action sear device for machine guns having reciprocating action members, comprising a frame, a lever pivoted to swing in a plane with the path of the action member from an initial position to an operated position and having a short arm extended toward said path and inclined in the direction of its said swing, a sear pivoted on the said arm having a heel part movable into said path and having a forwardly extended operating arm, a second lever pivoted with the first lever, a sear spring under tension between the sear and said first lever urging the sear heel toward said path, the second lever having a rack sector at its outer part, a revolvably mounted gear meshed with the rack an escapement operatively associated with the gear to retard movement of the latter in one direction, a resilient connection between the levers, a cam positioned to slidably support the end of said operating arm of the sear, and means to move said cam to vary its angular position at will in relation to the direction of movement of said short arm.

20 4. The structure of claim 3, in which said device includes a frame adapted to constitute part of a gun frame assembly and having a trigger guard and hollow pistol type grip extended downwardly therefrom, said levers being extended into said grip for the described movement therein, said means to move said cam comprising a lever pivoted above the guard and having a rearwardly extended arm under said cam and having a finger piece extended into the guard spring-urged to a forward released position.

25 5. The structure of claim 3 in which said device includes a frame adapted to constitute part of a gun frame assembly and having a trigger guard and hollow pistol type grip extended downwardly therefrom, said levers being extended into said grip for the described movement therein, said means to move said cam comprising a lever pivoted above the guard and having a rearwardly

extended arm under said cam and having a finger piece extended into the guard spring-urged to forward released position, said escapement comprising a V-toothed wheel, a pendulum pivoted therebelow in the grip and having pallet portions engaging the wheel, and a one way clutch connection between the gear and wheel.

6. In a rate of fire retarding mechanism for a rapid-fire gun, a firing member movable between cocked and firing positions, a sear, means mounting said sear in position to releasably engage and hold said member in cocked position, said means being movable between first and second positions in which said sear is at lesser and greater distances, respectively, from said member, means yieldingly resisting movement of said sear mounting means from first to second positions, a trigger movable in a firing direction to first and second positions in sequence, cam means operable by and in response to movement of said trigger to the first of said sequential positions to move said sear so that said sear is released from said member in response to movement of said sear mounting means to second position and movable stop means effective in one position to limit movement of said trigger to its first said sequential position, said stop means, when moved to another position, permitting movement of said trigger to its second sequential position wherein said sear is held clear of said firing member for all positions of said sear mounting means.

7. The structure of claim 6 wherein the mounting means for the sear comprises a first lever with a sear-carrying arm having an initial elevated position inclined from its pivot toward and in the direction of the firing motion of said firing member, a separate second lever pivoted for movement in the same direction as the first, a spring connected between the sear and first lever, means limiting relative movement of the levers under urging of said spring, yieldable means engaged between the levers to limit opposite movement of the levers by pressure of the firing member on the sear, means to retard movement of the second lever under pressure of the firing member on the sear, said sear having a forwardly extended operating arm, a sear operating means connected between the trigger and sear said last-named means being operative to let off the sear at a forward position only of the sear on said first-named lever arm and firing position of the trigger, said spring between the sear and first lever being operative to move said levers to initial positions while the sear is free of the firing member.

8. The structure of claim 6 wherein the sear-mounting means comprises a pivoted lever arm having an initial elevated position inclined from its pivot in the direction of firing motion of said firing member, said sear being a lever of the first order pivoted on and adjacent the extremity of said lever arm and having a heel extension to engage and hold the firing member in cocked position, yielding means urging said lever arm to said initial position and yieldable to pressure of the firing member on the heel of the sear, said yielding means comprising escapement means connected with said lever arm to oppose movement of the latter by the firing member and yieldable freely to return movement of the lever arm, said sear having an operating arm extended in the direction of firing movement of the firing member, said cam means extended from near the pivot of the sear in said direction of firing movement between the sear and trigger and receiving

said operating arm slidably thereon, said trigger being operable to engage and vary the pivotal position of said cam means.

9. In a rate-of-fire-retarding mechanism for a rapid-fire gun, a firing member mounted for reciprocation in a rectilinear path between cocked and firing positions, a cam element adjacent said firing member and having a cam surface pivotable from a first position generally parallel with said path to a second position inclined toward said path, a trigger operable to move said cam element from first to second position, a first lever pivoted about an axis generally perpendicular to said path, a sear pivoted on one end of said lever between said member and element and having one end engaging said cam element to be pivoted thereby, the other end of said sear being releasably engageable with said member to hold the same in cocked position, said sear being pivoted to release said member, only when said cam element is in said second position, by and in response to pivotal movement of said lever to predetermined position, and time-delay means acting on said lever to retard movement thereof to said position.

10. A mechanism as recited in claim 9, said cam element being pivotable by said trigger to a third position in which said sear is pivoted to a position free of said firing member, for all positions of said lever, and adjustable stop means cooperating, in one position of adjustment, with said trigger to limit movement of said cam element by said trigger, to the second position only of said element, said stop means, in a second position of adjustment being free of said trigger.

11. The mechanism recited in claim 9, said time-delay means comprising a second lever pivoted coaxially with said first lever and movable therewith to said predetermined position, spring means urging said levers apart, stop means limiting the angular separation of said levers under the urge of said spring means, and escapement means acting upon said second lever to delay the movement of said levers as a unit to said predetermined position.

12. In a firing mechanism, a reciprocating firing member, a sear pivoted thereadjacent having a heel movable and spring-urged into the path of the firing member and having a forwardly extended operating arm, a cam having a cam face under said arm, means responsive to operation of the firing member to move the cam and sear divergently, and then convergently with the cam oblique to the path of their relative movement for let-off, means to retard said convergent movement, said cam being a member pivoted below said sear arm and receiving the end of the latter slidably thereon, a spring-loaded trigger pivoted below and forwardly of said cam, said trigger having a finger piece for its operation and having an arm extending rearwardly under said cam for the purpose described.

13. In a firing mechanism, a reciprocating firing member, a sear pivoted thereadjacent having a heel movable and spring-urged into the path of the firing member and having a forwardly extended operating arm, a cam having a cam face under said arm, means responsive to operation of the firing member to move the cam and sear divergently, and then convergently with the cam oblique to the path of their relative movement for let-off, means to retard said convergent movement, said cam being a member pivoted below said sear arm and receiving the end of the latter slidably thereon, a spring loaded trigger pivoted

below and forwardly of said cam, said trigger having a finger piece for its operation and having an arm extended rearwardly under said cam for the purpose described, said cam having at least one step part thereunder, a dog pivoted adjacent said trigger arm having a spring supported arm under the trigger arm and having an upstanding rest swingable therewith under said step under firing movement of the trigger.

14. In a firing mechanism, a reciprocating firing member, a sear pivoted thereadjacent having a heel movable and spring-urged into the path of the firing member and having a forwardly extended operating arm, a cam having a cam face under said arm, means responsive to operation of the firing member to move the cam and sear divergently, and then convergently with the cam oblique to the path of their relative movement for let-off, means to retard said convergent movement, said cam being a member pivoted below said sear arm and receiving the end of the latter slidably thereon, a spring loaded trigger pivoted below and forwardly of said cam, said trigger having a finger piece for its operation and having an arm extended rearwardly under said cam for the purpose described, said cam having at least two step parts at different levels thereunder, a

dog pivoted adjacent said trigger arm having a spring supported arm under the trigger arm and having an upstanding rest swingable therewith under respective extents of said step firing movement of the trigger, said trigger and cam having movement to an extreme position to clear the sear from said firing member throughout operation of the firing member, said sear having operative relation to the firing member only at an intermediate position of the trigger and cam, and means operable at will to limit firing position of the trigger.
